US00D803539S

(12) **United States Design Patent** (10) Patent No.: **US D803,539 S**
(45) Date of Patent: **** Nov. 28, 2017**

(54) **SHOE INSOLE**

(71) Applicant: **Implus Footcare, LLC**, Durham, NC (US)

(72) Inventors: **David B. Granger**, Lorena, TX (US); **Jacob Martinez**, Temple, TX (US)

(73) Assignee: **Implus Footcare, LLC**, Durham, NC (US)

(**) Term: **15 Years**

(21) Appl. No.: **29/583,247**

(22) Filed: **Nov. 3, 2016**

Related U.S. Application Data

(62) Division of application No. 29/540,561, filed on Sep. 25, 2015, now Pat. No. Des. 778,040.

(57) **CLAIM**

The ornamental design for a shoe insole, as shown and described.

DESCRIPTION

FIG. 1 is a perspective view of a shoe insole showing our new design;

FIG. 2 is a bottom view thereof;

FIG. 3 is a top view thereof;

FIG. 4 is a lateral side view thereof;

FIG. 5 is a front view thereof; and,

FIG. 6 is a back view thereof.

All surfaces not shown form no part of the claimed design.

1 Claim, 4 Drawing Sheets
